UNITED STATES PATENT OFFICE.

GEORGE EDWARD OCAIN, OF OAK PARK, ILLINOIS.

AUTO OR GAS ENGINE STARTER AND INDICATOR.

1,025,762.

Specification of Letters Patent.

Patented May 7, 1912.

Application filed February 17, 1911. Serial No. 609,250.

To all whom it may concern:

Be it known that I, GEORGE EDWARD OCAIN, a citizen of the United States, and a resident of Oak Park, in the county of Cook 5 and State of Illinois, have invented an Improvement in Auto or Gas Engine Starters and Indicators, of which the following is a specification.

This invention relates to a starter for multiple cylinder internal-combustion engines, the object being to provide means for dispensing with the dangerous operation of cranking such engines, which is commonly done on automobiles.

15 The starter is so constructed that the engine may be started without necessitating the driver leaving his seat, and the invention includes an indicator by which it may be instantly ascertained which of the several 20 cylinders is ready for ignition of the explosive charge.

The details of construction, arrangement, and operation of parts are as hereinafter described and claimed, and illustrated in 25 the accompanying drawing, in which—

Figure 1 is a central vertical longitudinal section of the starting apparatus, together with the indicators. Fig. 2 is a vertical transverse section through the apparatus, 30 the same being taken at right angles to the main section—Fig. 1. Fig. 3 is a cross section of the tapered valve plug, the same being taken at the center of any of the indicating chambers.

35 In Figs. 1 and 2, the numeral 6 designates the main body of the valve and indicator casing. In the main chamber of the body 6 is arranged a tapered plug valve 7 which is provided at one end with a handle 5 secured by a nut 19. The other end is adjacent to a hollow plug 13 which closes the valve chamber at that end and is provided with a spiral spring 28 which applies pressure to the valve, tending to hold it pressed 45 toward the right, so that wear is taken up or compensated for and a tight fit always insured. The body 6 has a series of enlargements projecting downward and provided with chambers or passages into which

50 are screwed tubes 21 having pet cocks which are numbered, respectively, 8, 9, 10, and 11.

As shown in Figs. 1 and 2, these pet cocks have transverse passages and an enlarged milled head by which they may be rotated 55 to bring such passages into or out of communication with passages 22 in the tubes 21.

The lower ends of the tubes 21 have extensions which screw into a manifold 12 connected by a pipe 12^a with a pressure carbureter (not shown), which is, in turn, connected with a hand or foot air-pump or air storage tank such as are employed on some automobiles for inflating the tires.

In the chambers 20^a are arranged ball valves 30 which normally seat downward by their own gravity. The valve plug is provided with transverse passages 20 which may be brought into registration with passages communicating with the chambers 20^a, as shown in Figs. 1 and 2. Other passages 20^b are formed in the valve at a right angle to the passages 20 and communicate therewith, as shown in Fig. 2. When the valve is adjusted, as shown in Figs. 1 and 2, the passages 20, 20^a are aligned and 20^b communicates with port 20^c where a pipe 25 from an engine cylinder is attached.

The upper side of the body 6 is provided with a series of tubular projections 26 corresponding to and communicating with the several passages or ports 27 that align with passages 20 of the valve when adjusted as in Figs. 1 and 2. In the chambers 29 of these tubular projections 26 is arranged a series of pistons 1, 2, 3, 4, having stems 35 which fit loosely and are slidable in screw plugs 15, 16, 17, 18, that are inserted in the outer ends of the tubular projections 26. The stems of these pistons are provided with enlarged flat heads 1^a, 2^a, 3^a, 4^a, respectively, to serve as visual indicators.

The operation of my invention will now be understood. The apparatus is ordinarily placed on the inside of and adjacent to the dash-board of an automobile in a position 95 convenient for access and operation. In order to stop the engine, disconnect or throw off the sparking attachment, but do not choke or throttle closely; then, as the engine comes to rest, throw the lever 5 into position shown in Fig. 1, whereby all the ports of the plug valve 7 will be opened, and the pressure in those engine cylinders which contain a charge ready to be ignited will cause the respective finder or plunger pistons 1, 2, 3, 4, to rise, as shown by dotted lines in Fig. 1. In other words, by such rise of the plungers or pistons 1-4, it is indicated which cylinders are ready to fire. Then the respective pet cocks 8 and 11 controlling communication with the manifold 4 are opened, as shown.

Before describing the starting of the engine, let it be assumed that the lever 5 of plug valve 7 is down instead of up, as represented in Fig. 1, but with the plug valve 7 in the same position shown in Fig. 2. Then, to start the engine, set the lever 5 in left-hand horizontal position or straight out from the dash-board, by which adjustment the blank portion of the valve will cover the ports 27 leading to the indicator chambers in which the pistons 1, 2, 3, 4 are located. This will also leave the valve ports communicating with the pipes 25 leading to the engine. Then by strokes of the foot or hand air-pump, air may be forced through the pressure carbureter, whereby it will take up gasolene vapor, thus forming a firing mixture which, entering the manifold 12, will pass through the open pet cocks 8 and 11 and through ports 20^a and 23 to the two cylinders 1 and 4 into the two cylinders on the engine which are ready to fire. Then throw on the sparkers and the engine will run. After the engine has begun to run, the lever 5 should be adjusted to place the valve in such position that it will cover ports leading to the engine cylinders; then close the pet cocks to the manifold.

In order that the apparatus may serve as 30 a finder or indicator of cylinders which are next ready to fire, after the engine has been stalled or stopped, first open the plug valve 7, with the lever 5 straight down; then open the pet cock 8 and admit gas under 35 pressure to the manifold 12, and if the engine cylinder piped to 20 is next ready to fire, it will hold the pressure and the finder 1, 1^a will rise and visually indicate this; but if the cylinder referred to does not hold gas, 40 the exhaust on intake valve will open and the finder will not indicate. Proceed in this manner until two finders indicate, and then leave their respective cocks open to the manifold, the others being closed, and raise 45 the lever 5 to horizontal position; then the starter is ready for the starting operation.

It is obvious that this starter and finding apparatus is not limited to four cylinders, but that it may be applied to six or eight

cylinder engines by the addition of valve 50 and finder chambers as needed.

The function of the ball valves 30 is to prevent back-firing into manifold 12. They also allow the spark to be thrown on as soon as the explosive mixture is forced into 55 cylinders, without first closing the plug valve 7.

What I claim is:—

1. The improved gas-engine starter and indicator, consisting of a body having a longitudinal bore or chamber and on its upper side a series of lateral chambers communicating with the said bore, pistons slideable in such chambers and having projecting heads that serve as visual indicators or finders, a plug valve adapted to rotate in the bore and having transverse passages, each formed of communicating ports in T form, the chambered body having also lateral passages, and pipes from the engine cylinders to be started secured in said passages, tubes pendent from the chambered body and communicating with openings in the latter which register with the plug passages, pet-cocks in said tubes, and a manifold common to, or connecting, the tubes, and adapted to receive an explosive gas-mixture, as shown and described.

2. The combination of a body having a lengthwise bore and ports leading out therefrom on the top, the side, and the bottom, of said body, pistons slideable in the upper ports, engine pipes communicating with the side ports and tubes connecting with the bottom ports, and provided with pet-cocks, ball valves seated downward in said bottom ports, and a rotatable plug arranged in the body and having transverse T-shape ports adapted to communicate with the several ports of the body, as shown and described.

In testimony whereof, I make statement that this invention is a product of my own brain, and I affix my signature in the presence of two witnesses.

GEORGE EDWARD OCAIN.
